(57) **CLAIM**

I claim the ornamental design for a fuel efficient portable stove for use with a round-bottom pot, as shown and described.

DESCRIPTION

FIG. 1 is a top view of the stove.

FIG. 2 is a bottom view of the stove.

FIG. 3 is a front view of the stove.

FIG. 4 is a side view of the stove.

FIG. 5 is a rear view of the stove.

FIG. 6 is a perspective three-dimensional view from above of the stove; and,

FIG. 7 is a perspective three-dimensional view from below of the stove.
